HOSIERY FORM

Filed July 3, 1928

UNITED STATES PATENT OFFICE

WILLIAM J. DE WITT, OF AUBURN, NEW YORK, ASSIGNOR TO THE SHOE FORM CO., INC.,
OF AUBURN, NEW YORK, A CORPORATION OF NEW YORK

HOSIERY FORM

Application filed July 3, 1928. Serial No. 290,252.

The object of this invention is to provide a hollow hosiery form on which hosiery is displayed and to provide a process for making such form. The form embodying this invention and selected for the purpose of illustration thereof is one which normally takes the natural position assumed when the human foot is in a shoe, the heel being higher than the toe, without placing the hosiery under any unusual strain or marking or defacing it in any way. A form embodying this invention, when standing upright upon a surface, will normally assume a position with the forepart resting upon the surface and the heel portion raised above the surface, without the application of an external bracing supporting means which, prior to this invention, has been thought necessary.

Other objects of the invention reside in the details of construction and process of manufacture hereinafter set forth in the specification and illustrated in the drawings, in which:

Fig. 1 is a side elevation, partly broken away, of a hosiery form embodying this invention and adapted for the display of hose or socks;

Fig. 2 is an enlarged bottom plan view of the forepart of the form illustrated in Fig. 1;

Fig. 3 is a sectional view taken along the line 3—3 of Fig. 2;

Fig. 4 is a sectional view taken along the line 4—4 of Fig. 1, illustrating the joinder between two parts of the form;

Fig. 5 is a view similar to Fig. 4, illustrating a modification of the joinder there illustrated;

Fig. 6 is a side elevation, partly in section, of a hosiery form made up of a foot form and a leg form before the forms are assembled;

Fig. 7 is a view illustrating one way of joining the foot and leg forms shown in Fig. 6; and

Fig. 8 is a view illustrating a hosiery form comprising a toe and leg form.

The hosiery form designated generally by the reference numeral 1 replicates the human lower leg and foot, and comprises a foot form 2 and a leg form 3. The foot form 2 is similar in many respects to the shoe form shown in my Patent No. 1,632,954, dated June 21, 1927, certain features, however, having been added thereto. The foot form 2 comprises a heel portion 5, a forepart or toe portion 6, and a sole 7. The forepart 6 includes a bottom flange 8 which is connected across the ball of the foot by a bridge or cross piece 9. The bridge 9 is attached to the bottom of the flange 8 and is preferably, although not necessarily of the two-ply construction set forth in my Patent No. 1,585,284, dated May 18, 1926, the ends of the plies being separated and straddled over the edges of the flange 8. A strip 10 is secured to the upper face of the bridge 9 and provided at its forward end with a flange 11 which projects into the hollow of the form, preferably at right angles to the body portion of the strip, and is spaced back from the front edge of the bridge 9 to provide a recess 12. In the toe of the forepart 6 is inserted a weight 15, which preferably fills the toe and is supported upon the flange 8 and in the recess 12 formed by the bridge 9 and the strip 10. The flange 11 of the strip 10 bears against the inner end of the weight 15 and thus holds it securely in its position in the toe.

The leg form 3 is substantially tubular, although it is given an outward contour which corresponds to that of the lower part of a leg. The forms 2 and 3 are made from blanks of flexible sheet material which may be molded in any suitable manner, and which are preferably of celluloid or of other like material having similar characteristics. The material may be colored either before or after molding if it be desired to do so.

In the embodiments of the invention here illustrated, the foot form 2 and the leg form 3 are made separately and then joined at sub-

stantially the ankle line. In Fig. 4 is illustrated one form of joinder in which the upper edge 20 of the foot form is depressed slightly to provide a shoulder 21 which receives the 5 lower end 22 of the leg form. The edge 23 of this end may be shaped so that it will coincide with the outer contour of the edge 20. These parts may be secured together in any suitable manner, preferably by adhesive ma- 10 terial which may be a cement, or which may be a solvent by which the material from which the forms are made is softened. In any case, the foot form 2 and the leg form 3 are permanently united so that the entire form 1 may be handled as a unit, the flange 24 stiffening the joinder. 15

In place of the joinder illustrated in Fig. 4, that shown in Fig. 5 may be employed in which the foot form 2 and leg form 3 each 20 terminate at their adjoining ends in flanges 25, 26, respectively. These flanges project into the hollow of the form and may be firmly united in any desired manner, such as that previously referred to or by means of rivets 25 if desired.

Figs. 6 and 7 illustrate another means for preparing the hosiery form. In these figures the foot form 2 is shown completely finished while the leg form is shown as a substantially 30 cylindrical tube 30. The tube 30 is of such diameter that it will enter the hollow of the foot form, and is provided at its lower edges with notches 31. The leg form 3 is inserted into the hollow of the foot form 2 and the as- 35 sembed forms are then placed in a two-part mold or die 32 which completely surrounds and embraces the forms 2 and 3. The mold 32 is hollow and is given an internal confor- 40 mation which corresponds to the conformation desired of the finished form. A steam bag 35 is introduced into the tube 30 and then caused to expand, forcing the walls of the tube 30 outwardly into contact with the walls of the mold 32 and into contact with 45 the inner surface of the form 2. The heat in the bag 35 softens the material of the tube 30 so that it will assume the desired position. This application of heat and pressure by the steam bag thus unites the contracting sur- 50 faces of the leg and foot forms and produces a unitary hosiery form.

The steam bag 35 completely fills the forms as shown in Fig. 7 and after sufficient heat and pressure has been applied air is intro- 55 duced into the bag to cool the form and set the material in the desired position. After the form has been removed from the mold 32 the joinder is treated with acetone in order to connect the overlapping portions. If the 60 upper edge of the foot form 2 is softened with acetone and then given a rubbing and smoothing action practically all trace of the joinder can be removed. The joiners shown in Figs. 4 and 5 can be similarly treated with similar 65 results.

In place of the foot form 2 including the heel portion 5 a foot form 40 which comprises only the toe may be used as shown in Fig. 8. The joinder between the forms can thus be made nearer the toe so that if a shoe 70 be placed on the form the joinder will be entirely concealed thereby. The leg form 41 illustrated in Fig. 8 includes the heel portion 42. The forms 40 and 41 are preferably united in a mold similar to the mold 32 by the use 75 of a steam bag, the form 41 being produced from a tube in the manner previously de- scribed above.

Hosiery is slipped on the form 1 and the form placed on a supporting surface. The weight 15 causes the form to assume the position shown in Fig. 1 at all times. The form may be placed on a support 45 with the heel extending beyond the edge thereof as shown in Fig. 1 and will thus attract considerable 80 attention. When used to display full length hose the end of the hose above the form may be tucked in out of sight as indicated on Fig. 1.

It will be noted that the form herein de- 85 scribed is transparent or translucent and an electric bulb or other source of light may be inserted if desired to bring out more distinctly the texture and pattern of the hosiery displayed thereon. Since the material of which 90 the form is made is flexible the hosiery can be slipped thereon without putting it under any undue strain, the form yielding when 95 necessary. Moreover the flexibility of the form is of advantage in filling the hosiery 100 and if the size of the hosiery be properly selected the form will present the appearance 105 of a well hosed human leg and foot.

The form herein described may be used 110 for displaying shoes in addition to hosiery 115 with very pleasing results. When so used the hosiery is first slipped onto the form and then the hosed form inserted into a shoe. In place of hosiery the outer surface of the form 1 may be treated to imitate hosiery being 120 given striations which simulate the texture 125 of the hosiery and being tinted in any de- sired color. One way of so treating the form is by applying to the outer surface a solvent, such as acetone, which will temporarily 130 soften the surface, applying a fabric of the desired texture to the softened surface thereby producing striations therein and removing the fabric before the surface has entirely hardened again. The surface of the form retains the imprint of the fabric and when a shoe is slipped thereon the effect is that of a hosed form. On Fig. 8 of the drawings the reference numeral 50 is applied to designate a portion of the outer surface of a form which has been provided with striations as suggested above. In most cases the entire outer surface of the form would be so treated but it is felt that the showing here made is sufficient for the purposes of this application 135

and that it is not necessary to extend it over the entire surface of the form.

Instead of permanently uniting the leg and foot form as described above the forms may be removably united so that the foot form could be used either alone or with the leg form attached thereto. While the process of making the leg form illustrated in the drawings and described herein includes the 5 use of the mold or die 32 or a similar device, it has been found feasible to omit the mold or die and employ a steam bag in the shape of a leg, so that the leg form is given the desired contour by the inflation of the bag 10 alone.

The form illustrated is one on which half hose or socks can be completely displayed and can only be used for full length as suggested in Fig. 1. It is obvious, however, that 15 a form adapted to display completely full length hose could be provided if desired without departing from this invention, and while the invention has been illustrated in certain embodiments it is not limited thereto, since 20 other embodiments could be made without departing from the spirit and scope of the invention as set forth in the following claims.

I claim:

1. A hosiery form replicating the human 25 leg and foot and having a weight at the forepart of the foot portion so that the form normally takes the natural position assumed when the human foot is in a shoe, the heel being higher than the toe.

2. A form replicating the human foot and 30 having a weight at the forepart thereof so that the form normally takes the natural position assumed when the human foot is in a shoe, the heel being higher than the toe.

3. A hollow hosiery form replicating the 35 human leg and foot and comprising a foot form and a leg form and a weight in the forepart of the foot form so that the hosiery form normally takes the natural position assumed 40 when the human foot is in a shoe, the heel being higher than the toe.

4. In a hollow hosiery form including a 45 foot form open at the forepart, a flange at the open portion, a bridge across the open 50 portion and a weight in the forepart bearing upon the flange and bridge.

5. In a hollow hosiery form including a 55 foot form open at the forepart, a flange at the open portion, a bridge across the open portion, a weight in the forepart bearing upon the flange and bridge, and a strip carried by the bridge and bearing against the weight to hold it in place in the forepart of the form.

6. In a hollow hosiery form including a 60 foot form open at the forepart, a flange at the open portion, a bridge across the open portion, a weight in the forepart bearing upon the flange and bridge, and a strip carried by the bridge and having an upwardly 65

extending flange which bears against the weight to hold it in place in the forepart of the form.

7. A hosiery form replicating the human leg and foot the bottom of the toe portion 70 being flat so that the form normally stands upright, and having a weight in the foot portion so as to hold the form in such position.

Signed by me at Auburn, New York, this 75 22nd day of March, 1928.
